UNITED STATES PATENT OFFICE.

FREDERICK M. TURCK, OF ROSEBANK, NEW YORK, ASSIGNEE TO THE CARTER-CRUME COMPANY, LIMITED, OF TORONTO, CANADA, A CORPORATION OF ONTARIO.

WEB-PRINTING PRESS.

1,164,968.

Specification of Letters Patent. Patented Dec. 21, 1915.

Application filed November 27, 1908, Serial No. 464,771. Renewed August 26, 1913. Serial No. 786,793.

To all whom it may concern:

Be it known that I, FREDERICK M. TURCK,
a citizen of the United States, and resident
of Rosebank, in the county of Richmond
5 and State of New York, have invented cer-
tain new and useful Improvements in Web-
Printing Presses, of which the following is
a specification.

a specification.

The invention relates to improvements in web-printing machines in which the web is printed upon both surfaces, laterally severed, and delivered either as flat sheets or to a folder as may be desired, the invention being particularly adapted for multi-color work, such as the printing of labels and magazine-covers, and for similar products requiring variable sizes of sheets.

The object of the invention is to provide
means for printing and cutting such vari-
20 able sizes of sheets upon the same mecha-
nism with comparatively slight change or
adjustment of the parts thereof; and the in-
vention further consists, in the construction,
arrangement and combination of the several
25 parts hereinafter shown, described and
claimed.

In describing the invention in detail, reference is had to the accompanying drawings, forming a part of this specification, and wherein like characters of reference are used to designate corresponding parts throughout the several views, and in which;

Figure 1 is a sectional side elevation of the improved printing and cutting machine embodying my invention; and Fig. 2 is a ground plan of the same.

In the drawings, numeral 1 indicates the base of the machine, upon which are fixedly secured the front and rear main frames or standards, respectively numbered 2 and 3, and upon the base are also mounted the movable front and rear frames, indicated respectively by 4 and 5, the latter frames being provided with rollers 6, adapted to engage tracks or grooves 7 in the base for maintaining alinement with the main frames. A third set of front and rear frames 8 and 9, respectively, slide upon the movable frames 4 and 5, and are arranged for alined longitudinal adjustment therewith by suitable adjusting screws 10. The several sets of frames are provided with ap-

propriate cross-braces, and within the frames are rotatably mounted the impression-cylinders 11, 13, 15 and 17, and the corresponding form-cylinders 12, 14, 16 and 18, the latter cylinders carrying detachable forms or printing-plates adapted to be changed to suit the required lengths of printed surfaces or sheets and which coact with suitable inking mechanism, indicated by the distributing-cylinders 19 and the form rollers 20. The main frames 2 and 3 are further provided with bearings in which is mounted a shaft 21, loosely supporting a frame, comprising the suitably-braced side arms 22, having bearings corresponding with oppositely-disposed boxes on the main frames in which are coaxively mounted for rotation the cutting-cylinders 23 and 24, the feed-rollers 25 and 26, and the perforator-shafts 27 and 28. The side arms are provided at their outer ends with pivotally-mounted adjustable connection-links 29, the lower ends of which engage the eccentric ends of a cross-shaft 30, which latter is mounted to make a partial revolution in the main frames and is provided at one end with a hand-lever 31, by which the mechanism carried by the side arms may be raised to permit the threading of the web. Also for the introduction of the web through the press the lower impression-cylinder of each printing-couple is journaled in vertically-movable boxes, supported upon slidable bars 32, shown in dotted lines, and preferably mounted in perforations or cores formed centrally in the several frames. The bars 32 engage eccentric portions formed on the cross-shafts 33, all of which shafts are adapted for partial revolution in the frames for raising and lowering said lower cylinders, the actuating mechanism for the shafts being of common construction, not shown.

Mounted in the frames of the press for co-
action with the form-cylinders 14, 16 and
18, is a web-compensating device or frame
comprising the two rock-shafts 34, upon
which are fixedly mounted the double-armed
levers 35 and 36, having bearings upon
their upper ends in which are journaled the
rollers 37 for supporting and guiding the
web, a belt-roller 38 being similarly mount-
ed in the ends of the lower arms of levers 36.

Connecting these latter arms with pivotal connection-straps 39, are a pair of similarly depending arms 40, fixedly secured to rock-shaft 41 and rotatably supporting a belt-
5 roller 42, corresponding with roller 38. Loosely mounted upon the rock-shafts 34 and 41 and coacting with rollers 38 and 42, are rollers 43, carrying the feeding-belts 44, the latter being frictionally driven by
10 the auxiliary feeding-roller 45, rotatably mounted in the main frames and positively driven from a change-gear hereinafter described.

Adjacent the form-cylinder 12 is a compensating-frame composed of a pair of side bars 46, having cross-braces 47, adapted for pivotal support upon the oscillatory arms 48 and 49, the arms being fixedly supported upon the rock-shafts 50, journaled in the
15 main frames of the press. In the compensating-frame are journaled the rollers 51, adapted to support and guide the web in substantially horizontal printing relation with the adjacent printing-couple, which
20 manner of web support corresponds with that of rollers 37 in relation to their printing-couples. The arms 48 and 36 are connected together by the links 52 and the cross-connection levers 53, the latter being supported upon extensions 54 of the frames and pivotally arranged therewith and with the links and arms to permit of the latter's oscillation in opposite directions. Connection-links 55, provided at one end with bifurcated
25 jaws 56, serve to detachably connect arms 35 and 40. These links are further provided with suitable longitudinally-adjusting means, not shown, for the accommodation of the adjustment of the movable frames 4
30 and 5.

Journaled in the main frames and adapted for frictional engagement with belts 44, is a feeding-cylinder 57, having a diameter and speed similar to that of the several form
35 and impression cylinders. Below the feeding-cylinder and coacting therewith is a compensating-cylinder 58, provided with a detachable peripheral contact-surface 59, which engages the web during its travel
40 through the press and exerts a pressure thereon to urge the belts in contact with the feeding-cylinder 57, and with which it is driven in unison and at a constant speed of rotation by suitably disposed gearing arranged exteriorly of the rear main frame 3.
45 In the rear main frame is also journaled a main driving-shaft 60, provided with an exterior bearing 61, and having a belt-pulley 62 and a pinion-gear 63, the latter, shown as a
50 dotted circle in Fig. 1, intermeshes with the intermediate gear 64, from opposite sides of which are driven in unison the several printing-cylinders and their respective inking mechanism, the gearing for form-cylinders
55 12 and 14 being arranged in a straight line

and including the intermediate 65, which engages gear 66, secured to the end of the shaft of form-cylinder 12, similar gears being fixed upon the shafts of the other form-cylinders, and all of which engage corresponding gears on the impression-cylinders. Exterioly of the driving-gears of form-cylinders 14, 16 and 18, are secured bevel-gears 67, which engage corresponding bevel-gears 68 and 69, secured to way-shaft 70, the latter being rotatably mounted in bearings 71, fixedly secured to the rear movable frames. This shaft is longitudinally fixed, relatively with the movable frames 4 and 5, by the collar 72 and the hub of the fixedly-secured bevel-gear 68, the bevel-gears 69 being adjustably fixed upon the shaft to permit the adjustment of the movable frames. Disposed below the bevel-gear on the shaft of form-cylinder 14 and engaging therewith, is a bevel-gear 73, secured to the vertical shaft 74, which latter is rotatably mounted in suitable bearings secured to the rear main frame and is provided at its lower end with a bevel-gear 75, which engages a corresponding bevel-gear 76, secured to the shaft of the feeding-cylinder 57 and shown by dotted circles in Fig. 1. Engaging bevel-gear 76, is a corresponding gear 77, secured to the way-shaft 78, the latter being rotatably mounted in bearings 79, secured to the rear main frame of the press. Upon the opposite end of the way-shaft is secured a bevel-gear 80, engaging the corresponding bevel-gear 81, the latter being fixed to the intermediate gear 82, which is loosely mounted upon a short stub-shaft 83, secured to the rear main frame of the press. Also mounted upon the stub-shaft 83 is an adjustable arm 84, carrying an intermediate gear 85, which intermeshes with the intermediate 82 and also engages the gear 86, secured to the lower cutting-cylinder 24, for constantly driving the latter at a uniform rate of speed a number of revolutions corresponding to that of the several printing-cylinders, in order that a sheet may be cut at each revolution of the latter. Vertically-adjustable bearings are provided for the cutting-cylinders to permit of the suitable engagement of their cutting members, which members are radially-adjustable in their respective cylinders for cutting variable lengths of sheets, it being evident that a radial change in the cutting members will produce a proportional change in the length of the sheet cut at each revolution of the cutting-cylinders. Removably secured upon the rear ends of the shafts of said cutting-cylinders are a pair of change-gears corresponding in radius to the radial change in the cutting members and adapted to positively drive the cylinders together, the gear for the upper cylinder being indicated by numeral 87 and more clearly shown in Fig. 2, the gear for the lower cylinder being in- 130

dicated by 87^a, and, as herein shown, it corresponds in diameter with the fixed gear 86 and is laterally disposed therewith.

Upon the vertical adjustment of the lower cutting-cylinder 24, the arm 84 is likewise adjusted to afford the necessary engagement between the intermediate gear 85 and the fixed gear 86, secured to the lower cutting-cylinder. It will be seen that the change-gears are arranged in a second train, the lower gear 87^a engaging the intermediate 88, rotatably mounted upon the bracket 89, the latter being adjustably supported upon the frame for the accommodation of the variable sizes of change-gears. The intermediate 88 engages gear 90 for driving the lower feed-roll 26, which gear in turn, through the intermediate 91, drives a gear on the lower perforator-shaft 28, which latter engages the corresponding gear 92, secured to the upper perforator-shaft 27. This train of gears is further extended from the lower perforator-shaft by the intermediate 93, which is loosely mounted upon a stud 94, fixed in the frame. Laterally secured upon the intermediate is a bevel-gear 95, which engages a corresponding bevel-gear 96, fixed upon one end of the way-shaft 97, which latter is rotatably mounted in bearings 98 and provided at its opposite end with a bevel-gear 99, which engages and drives a corresponding bevel-gear 100, fixed upon the end of the shaft carrying the auxiliary feeding-roller 45.

The several gears leading from the change-gears on the cutting-cylinders are so proportioned as to maintain a common peripheral speed of the cutting-cylinders 23 and 24, the lower feed-roll 26, the disks on perforator shafts 27 and 28, and the auxiliary feeding-roller 45. The upper feed-roll 25 is preferably driven by frictional contact with the lower positively driven roll 26, and in place of an upper roll, a series of independently-adjustable pulleys may be substituted and arranged to vary the amount of feeding tension on the web. The disks upon the perforator-shafts 27 and 28 are adapted to coöperate to longitudinally perforate or sever the web for certain classes of work only, and do not form an essential feature of this invention. The intermediate gears used for driving the several cylinders and rollers are indicated in dotted circles in Fig. 1, and are arranged to run loose upon studs or shafts in the usual manner.

Between the movable frames 4 and 5 is suitably mounted the paper-roll 101, from which the web is led over the guiding-rollers 101 and 103 to the endless belts 44 and along with which it travels between the feeding-cylinder 57 and compensating cylinder 58 to the auxiliary feeding-roller 45, the guiding-rollers being rotatably mounted in the frames of the machine; also the rollers 103

and 45 are arranged with relation to their opposing rollers 43 to exert a tension therebetween to jointly propel the belts and web. From the feeding-roller 45 the web is led over a registering device (adapted for use when the web is provided with previously imposed characters), comprising a shaft 104, mounted for rotative adjustment in the arms 36, and carrying a guiding-roller 105, loosely mounted for rotation thereon. Fixedly secured to the shaft at opposite ends of the roller are a pair of arms 106, in which is journaled a roller 107, adapted for oscillatory adjustment with the shaft to vary the length of the web between the guiding-roller 105 and the superposed roller 37, journaled in the upper ends of arms 36. From this latter roller the web passes, in a substantially horizontal plane, below the form-cylinders 14, 16 and 18, and over the opposite roller 37, journaled in the upper ends of arms 35, to the guiding-rollers 108, 109 and 110 and thence to the registering-roll 111 and the guiding roller 112. The guiding-roller 108 is loosely mounted for rotation upon the shaft 34, and the similar rollers 109, 110 and 112 are rotatively mounted in the frames. Registering-roll 111 is rotatively mounted in a pair of arms 113, which are secured to a shaft 114, the latter being mounted in the frames for the oscillatory adjustment of roll 111 to permit of varying the length of the web between rollers 110 and 112 for suitably registering with the printing-couple 11 and 12. The web passes from the guiding-roller 112 to the rollers 51, which support it in printing relation with form-cylinder 12, and from which it is led to the guiding-roller 115, and thence between the perforator-shafts 27 and 28, feeding-rolls 25 and 26, and the cutting-cylinders 23 and 24, from which it may be delivered by suitable devices either as flat sheets or conveyed to a folding-machine.

In order to facilitate the introduction of the web through the machine, the compensating-cylinder 58 is journaled in vertically-movable boxes, supported in like manner as described for the impression-cylinders of the printing couples, upon slidable bars 116, which engage eccentric portions formed on the cross-shaft 117, which latter is mounted in the main frames and adapted to make a partial revolution by the movement of hand-lever 118 for raising and lowering said cylinder.

In the travel of the web through the machine its normal speed is controlled by the feeding-rolls 25 and 26, in conjunction with the auxiliary feeding-roller 45 and the endless belts 44, these parts being positively driven from the lower cutting-cylinder by the change-gear 87^a corresponding to the gear 87 on the upper cutting-cylinder, it will follow that a change in the diameter

of these gears will cause a proportional change in the feeding action upon the web and cause its normal travel over the several rollers throughout the press to vary 5 accordingly. Assuming that the cutting-cylinders be adjusted to receive gears of the same diameter as those for the printing-cylinders and for the cylinders 57 and 58, the travel of the web throughout the press will 10 conform with the peripheral speed of the several cylinders mentioned and the machine will be adapted to print and cut the maximum length of sheets. For this length of sheet the compensating-cylinder 58 may be 15 lowered for disengagement with the feeding-cylinder 57, or it may be provided with a full peripheral contact-surface 59 and retained in its upper position where it will act as an additional feeder for the web. This 20 uniformity of web speed while printing the maximum length of sheets will produce no action upon the compensating devices, which include the several arms 35, 36, 48 and 49, all of which will be held as shown, at one 25 extreme of movement by the contractile spring 119, secured at one end to lever 35 and at its opposite end to a bracket 120, fixed upon the frame. If, however, shorter lengths of sheets are required, the cutting 30 members of the cutting-cylinders are adjusted accordingly and the corresponding gears provided therefor, also, the peripheral length of the contact-surface 59 for the compensating-cylinder 58 is made to conform 35 with the length of the desired sheet to be cut, and the same is securely adjusted upon the cylinder, and acts in unison with the several likewise-reduced forms or plates upon the printing-cylinders, indicated there- 40 on in solid lines. The contact-surface 59 is preferably composed of a flexible sheet of fibrous material, of a suitable thickness to afford a clearance for the independent return movement of the web over the uncov- 45 ered peripheral portion of the cylinder.

The several sets of printing-cylinders are adjusted in relation to their forms to jointly make their impressions upon the web in the same period of time, and it will be evident that 50 during the period in which the impressions are taken the impressed portion of the web must travel at a speed corresponding with that of the printing-surfaces, and as the peripheral length of these surfaces is reduced 55 in accordance with the required reduction in the length of sheet to be cut, the printing periods of time will likewise be reduced, and the intervals between the impressions will be correspondingly increased.

For sheets of reduced length, the consequent normal reduced speed of the web must be accelerated at the printing-cylinders during the period of impression, and for this purpose the arms 35, 36, 48 and 49 are re- 60 ciprocated by the action of the feeding-cyl-

inder 57 and the compensating-cylinder 58 in opposition to the contractile spring 119, the cylinders 57 and 58 having a peripheral speed corresponding with that of the printing-cylinders, as previously described. As 70 shown in Fig. 1, the several operative parts are positioned prior to the taking of the impression, the peripheral contact-surface on the compensating-cylinder being clear, the 75 arms 35, 36, 48 and 49 are retained in their backward extreme of movement, and the web is free to travel at its normal relatively-reduced speed. By the continued rotation of the several cylinders the peripheral contact-surface on cylinder 58 engages and accelerates 80 the portion of the web carried between the rollers 38 and 42 to an amount equaling its own peripheral speed. This acceleration is induced by the tension between the two coacting cylinders 57 and 58, causing a gradually increasing tension, due to the increase of speed, upon this portion of the web and its contacting belts which produces a relatively slow forward movement of the several connected arms in opposition to the 85 spring 119; the forward movement continuing during the action of the peripheral contact-surfaces and causing a correspondingly accelerated speed on the portion of the web engaged by the printing-cylinders which 90 conforms with the printing speed.

As the several printing-couples make their impressions at one time, and the couples including form-cylinders 14, 16 and 18 make their impressions successively upon the same 100 printing-surface, it is to be noted that the latter couples are centrally spaced apart to conform with the required length of sheet to be cut, the necessary spacing therefor being effected by the longitudinal adjustment of 105 the movable frames. For frames 4 and 5 this adjustment is accomplished by the screw-threaded connections 121, which are pivotally mounted at one end to the movable frames and are provided at their opposite 110 ends with bifurcated jaws 122, adapted for detachable connection to pins 123, fixed upon the main frames, and from which the movable frames may thereby be readily disconnected and sufficiently separated to afford 115 access to the center of the machine. With the adjustment of these frames a corresponding variation is made in the length of the connection-links 55.

As shown, the form-cylinders 14, 16 and 120 18 are adapted to print in separate characters or colors on one side of the web, and for perfecting or printing the opposite side thereof, form-cylinder 12 is employed, perfect register of the latter printing-surface 125 being effected by the registering-roll 111. It will thus be seen that the described mechanism is adapted for a wide range of work both as regards the length of sheet and the colors or characters printed.

I am aware that heretofore web-printing machines have been designed having constantly-rotating form-cylinders provided with partially-surrounding printing-plates 5 adapted to print a surface of less length than the maximum printing-circumference of the cylinders; but in such cases during the rotation of the blank portion of the cylinders the travel of the adjacent portion of the web 10 is completely stopped, and in some instances reversed, in order to secure register. In high-speed machines such variation in the movement of the web causes an excessive strain thereon, which is augmented by the 15 variation in the rotative action of its supporting-rollers, and produces an irregularity which impairs the register for high-class work.

The present invention is distinguished 20 from such machines in providing means for maintaining a constant travel of the web at the same rate of speed with respect to its supporting-rollers, and for accelerating the portion of the web engaged by the printing- 25 cylinders without affecting the rotative action of the supporting-rollers; the acceleration being so gradual as to be practically unnoticeable as regards the momentum of the web.

30 It is to be understood that the arrangement of the several parts of the machine may be modified to include a greater or less number of printing-couples, so disposed as to make a greater or less number of impressions 35 on one or both sides of the web. It is also evident that the invention is susceptible of various changes as regards its form, proportions and detail construction without departing from the essential spirit and scope 40 or sacrificing any of the advantages thereof.

What I claim as my invention and desire to secure by Letters Patent, is:

1. In a web-printing machine, the combination of continuously-rotating printing 45 mechanism adapted to receive forms for making impressions of variably less length than the maximum printing-circumference of said mechanism, means for supporting the web in printing relation therewith, 50 changeable means for advancing the web at a constant rate of speed relative to its supporting means and variably less than the printing speed, and means for advancing the supporting means to accelerate the web 55 to conform with the printing speed.

2. In a web-printing machine, the combination of continuously-rotating printing mechanism adapted to receive forms for 60 making impressions of variably less length than the maximum printing-circumference of said mechanism, means for supporting the web in printing relation therewith, changeable means for advancing the web at a constant rate of speed relative to its sup-

porting means and variably less than the 65 printing speed, means for advancing the supporting means to accelerate the web to conform with the printing speed during the impression, and means for retracting the supporting means at the end of the impression 70 to arrest the web relative to the printing mechanism.

3. In a web-printing machine, the combination of continuously-rotating printing mechanism adapted to receive forms for 75 making impressions of variably less length than the maximum printing-circumference of said mechanism, means for supporting the web in printing relation therewith, changeable means conforming with the variable lengths of forms for advancing the web at constant rates of speed relative to its supporting means, said rates of speed being less than the printing speed, means for advancing the supporting means to accelerate the 80 web to conform with the printing speed during the impression, and means for retracting the supporting means at the end of the impression to arrest the web relative to the printing mechanism. 90

4. In a web-printing machine, the combination of continuously-rotating printing mechanism adapted to receive forms for 95 making upon both sides of the web impressions of less length than the maximum printing-circumference of said mechanism, means for supporting the web in printing relation therewith, means for advancing the web at a constant rate of speed relative to its supporting means, said speed being less than 100 the printing speed, means for advancing the supporting means to accelerate the web to conform with the printing speed during the impression, and means for retracting the supporting means at the end of the impression 105 to arrest the web relative to the printing mechanism.

5. In a web-printing machine, the combination of continuously-rotating printing mechanism adapted to receive forms for 110 making upon both sides of the web impressions of less length than the maximum printing-circumference of said mechanism, means for supporting the web in printing relation therewith, means for advancing the web at a 115 constant rate of speed relative to its supporting means, said speed being less than the printing speed, means for advancing the supporting means to accelerate the web to conform with the printing speed during the 120 impression, means for retracting the supporting means at the end of the impression to arrest the web relative to the printing mechanism, and a registering device disposed in advance of the printing mechanism 125 operating upon the final printed side of web.

6. In a web-printing machine, the combination of printing devices including form,

- 6 impression and cutting cylinders, forms partially surrounding the form-cylinders and adapted to print a surface to be cut into sheets of less length than the circumference 5 of the printing-cylinders, a movable frame adapted to support the web in printing relation with said printing-cylinders, means for impelling the web at less speed than the printing velocity, a feeding-cylinder mounted adjacent the web and frame and having a peripheral speed corresponding with the printing speed, a compensating-cylinder in driving engagement with the feeding-cylinder, a contact-surface partially surrounding 10 the compensating-cylinder and having a peripheral length substantially corresponding with the length of sheet to be cut, said contact-surface being adapted to coact with the feeding-cylinder to engage the web, whereby a movement is imparted to the frame in a direction with the web for the acceleration of the latter during the impression, and means for moving the frame in an opposite direction for arresting the travel 15 of the web between the impressions thereof, substantially as described.
7. In a web-printing machine, the combination of continuously-rotating printing and cutting mechanisms, said printing mechanism adapted to receive forms for making impressions of less length than the maximum printing circumference thereof, means for supporting the web in printing relation with said printing mechanism, means for advancing the web at a constant rate of speed relative to its supporting means, said speed being less than the printing speed and common with the peripheral speed of the cutting mechanism, and means for advancing the supporting means to accelerate the web to conform with the printing speed.
8. In a web-printing machine, the combination of continuously-rotating printing and cutting mechanisms, said printing mechanism adapted to receive forms for making impressions of less length than the maximum printing circumference thereof, means for supporting the web in printing relation with said printing mechanism, means for advancing the web at a constant rate of speed relative to its supporting means, said speed being less than the printing speed and common with the peripheral speed of the cutting mechanism, means for advancing the supporting means to accelerate the web to conform with the printing speed during the impression, and means for retracting the supporting means at the end of the impression to arrest the web relative 40 to the printing mechanism.
9. In a web-printing machine, the combination of continuously-rotating printing and cutting mechanisms, said printing mechanism adapted to receive forms for making impressions of variably less length 65 than the maximum printing circumference thereof, means for supporting the web in printing relation with said printing mechanism, changeable means conforming with the variable lengths of forms to advance the web 70 at a constant rate of speed relative to its supporting means, said rate of speed being less than the printing speed and common with the peripheral speed of the cutting mechanism, means for advancing the supporting means to accelerate the web to conform with the printing speed during the impression, and means for retracting the supporting means at the end of the impression to arrest the web relative to the printing 75 mechanism.
10. In a web-printing machine, the combination with printing-cylinders, of a movable frame adapted to support a web having a normal speed of less than the printing speed, a feeding-cylinder rotatably mounted adjacent the web and having a peripheral speed conforming with the printing speed, a compensating-cylinder rotatably mounted upon the opposite side of the web adjacent 80 the feeding-cylinder, and a contact-surface partially surrounding the compensating-cylinder and adapted to coact with the feeding-cylinder to accelerate the web to conform with the printing speed.
11. In a web-printing machine, the combination with printing-cylinders, of a movable frame, rollers mounted therein and adapted to support the web for engagement with the printing-cylinders, a plurality of belt-rollers mounted in the movable frame and adapted to engage the web, a plurality of endless belts carried by the belt-rollers and adapted to engage the web, means for driving the belts and belt-rollers to impel 90 the web at less than the printing speed, and means operating upon the belts for accelerating the web to conform with the printing speed.
12. In a web-printing machine, the combination with printing-cylinders, of a movable frame, rollers mounted therein and adapted to support the web for engagement with the printing-cylinders, a plurality of belt-rollers mounted in the movable frame 100 and adapted to engage the web, a plurality of endless belts carried by the belt-rollers and adapted to engage the web, means for driving the belts and belt-rollers to impel the web at less than the printing speed, a feeding-cylinder rotatably mounted adjacent the belts and web and having a peripheral speed corresponding with the printing speed, a compensating-cylinder rotatably mounted adjacent the opposite side of the 105 belts and web and near the feeding-cylinder, a contact-surface partially surrounding the compensating-cylinder and adapted to co-

act with the feeding-cylinder to advance the frame during the engagement of the contact-surface whereby the web is accelerated to conform with the printing speed, and 5 spring-actuated means for retracting the frame upon the disconnection of the contact-surface.

13. In a web-printing machine, the combination with a plurality of relatively-adjustable printing-couples, of a compensating-frame comprising a plurality of interconnected oscillatory arms, web-supporting rollers adjacent the printing-couples and carried by the arms, a web-registering device 10 adjustably mounted upon the arms, and means for oscillating said arms.

14. In a web-printing machine, the combination of continuously-rotating printing mechanism adapted to make impressions of 20 variable lengths longitudinally of the web, means for supporting the web in printing relation therewith, means for advancing the web at a constant rate of speed relative to its supporting means, said speed being less 25 than the printing speed, means for advancing the supporting means to accelerate the web to conform with the printing speed, relatively-adjustable cutting-cylinders, radially-adjustable cutting members therefor, 30 interengaging driving means conforming with the adjustable cutting members, and driving means for rotating the printing mechanism and cutting-cylinders a common number of turns.

35 15. In a web-printing machine, the combination of a plurality of relatively-adjustable printing-couples, a pair of relatively-adjustable cutting-cylinders having radially-adjustable cutting members and interengaging driving gears therefor, driving means for rotating the printing-couples and cutting-cylinders a common number of turns, a compensating-frame adapted to support and guide the web in printing relation with the printing-couples, driving means in connection with the compensating-frame adapted to drive the web at a speed corresponding with the peripheral speed of the adjustable cutting members of the cutting-cylinders, driving means in connection with the compensating-frame adapted to accelerate the web to conform with the printing speed, and a web-registering device mounted upon the compensating-frame.

55 16. In a web-printing machine, the combination of a plurality of relatively-adjustable printing-couples adapted to print upon both sides of the web, a pair of relatively-adjustable cutting-cylinders having radially-adjustable cutting members and interengaging driving gears therefor, driving means for rotating the printing-couples and cutting-cylinders a common number of turns, a pair of interconnected compensat-

ing-frames adapted to support and guide 65 the web in printing relation with the printing-couples, driving means in connection with the compensating-frames adapted to drive the web at a speed corresponding with the peripheral speed of the adjustable cutting members of the cutting-cylinders, driving means in connection with the compensating-frames adapted to accelerate the web to conform with the printing speed, a web-registering device mounted upon the initial 70 compensating-frame, and a web-registering device disposed in advance of the final compensating-frame.

17. In a web-printing machine, the combination of impression mechanism, means 80 adapted to feed a web at a normal rate past said impression mechanism, and means adapted to grip a portion of said web and cause the rate of feed thereof relative to said impression mechanism to vary from the 85 normal rate.

18. In a web-printing machine, the combination of impression mechanism, means adapted to feed a web at a normal rate past 90 said impression mechanism, means adapted to sever said web into sheets, means adapted to adjust said severing means so as to sever the web into sheets of different lengths, and means adapted to grip a portion of said web 95 and cause the rate of feed thereof relative to said impression mechanism to vary from the normal rate.

19. In a web-printing machine, the combination of impression mechanism, means 100 adapted to operate said impression mechanism at a normal rate of speed, means adapted to sever said web into sheets, means adapted to vary the size of sheets severed without varying the rate of speed of the impression mechanism, means adapted to 105 feed said web past said impression mechanism at a normal rate, and means adapted to grip a portion of said web and cause the rate of feed thereof relative to said impression mechanism to vary from the normal 110 rate.

20. In a web-printing machine, the combination of impression mechanism, means adapted to feed a web at a normal rate past 115 said impression mechanism, and means adapted to frictionally grip a portion of said web and cause the rate of feed thereof relative to said impression mechanism to vary from the normal rate.

21. In a web-printing machine, the combination of impression mechanism, means adapted to feed a web at a normal rate past 120 said impression mechanism, and rotatable means adapted to grip a portion of said web and cause the rate of feed thereof relative to said impression mechanism to vary from the normal rate.

22. In a web-printing machine, the com-

bination of impression mechanism, means adapted to feed a web at a normal rate past said impression mechanism, and rotatable means adapted to frictionally grip a portion 5 of said web and cause the rate of feed thereof relative to said impression mechanism to vary from the normal rate.

23. In a web-printing machine, the combination of impression mechanism, means 10 adapted to feed a web at a normal rate past said impression mechanism, a pivoted frame adapted to support a portion of the web, and means adapted to grip said web to move said frame and thereby cause the rate of 15 feed of the web relative to said impression mechanism to vary from the normal rate.

24. In a web-printing machine, the combination of impression mechanism, means 20 adapted to feed a web at a normal rate relative to said impression mechanism, a pivoted frame adapted to support a portion of the web, and means adapted to grip a portion of said web and cause said frame to move so as to vary the rate of feed of the 25 web from said normal rate relative to said impression mechanism.

25. In a web-printing machine, the combination of a rotatable printing couple, a web supply device, means adapted to feed a 30 web from said supply device into operative relation to said couple at a normal rate of speed, and means adapted to grip said web between said supply and said couple and increase the speed of said web relatively to 35 said couple above said normal speed.

26. In a web-printing machine, the combination of a rotatable printing couple, a web supply device, means adapted to feed a web from said supply device into operative 40 relation to said couple at a normal rate of speed, and rotary means adapted to grip said web between said supply and said couple and increase the speed of said web relatively to said couple above said normal 45 speed.

27. In a web-printing machine, the combination of a rotatable printing couple, a web supply device, means adapted to feed a web from said supply device into operative 50 relation to said couple at a normal rate of speed, and means adapted to grip said web and increase the speed thereof to accord with the speed of the couple at the printing point.

28. In a web-printing machine, the combination of a rotatable printing couple, a web supply device, means adapted to feed a web from said supply device into operative 60 relation to said couple at a normal rate of speed, a movable member comprising oscillatory arms disposed to support said web between said supply device and said couple, and means adapted to grip said web and cause said arms and web to move in a di-

rection to increase the speed of the web to 65 accord with the speed of said couple at the printing point.

29. In a web-printing machine, the combination of a plurality of rotatable printing couples, a web supply device, means 70 adapted to feed a web from said supply device into operative relation to said couples at a normal rate of speed, means adapted to increase the speed of said web to accord with the speed of said couples at the printing points comprising a plurality of oscillatory members, over each of which the web passes, and means adapted to grip the web and cause said oscillatory members and the web to simultaneously move in directions to 80 increase the speed of the web to accord with the speed of said couples at the printing point.

30. In a web-printing machine, in combination, a printing couple comprising a 85 rotary element adapted to receive printing forms of different peripheral lengths, a web cutter adapted to be adjusted to successively sever the web between impressions thereon of said different forms, and means adapted 90 to feed a web cooperatively relatively to said rotary element and to said cutter, comprising a rotatable element adapted to receive web gripping surfaces of a length corresponding to said printing forms, respec- 95 tively.

31. In a web-printing machine, the combination of impression mechanism, a web-support movable relative to said impression mechanism, means adapted to feed a web at 100 a normal rate relative to said support, and means adapted to grip a portion of said web and cause said support to move, thereby varying the speed of said web relative to 105 said impression mechanism.

32. In a web-printing machine, the combination of impression mechanism, a web-support movable relative to said impression mechanism, means adapted to feed a web at 110 a normal rate relative to said support, and means adapted to grip said web intermittently and cause said support to move, thereby varying the speed of said web relative to said impression mechanism.

33. In a web-printing machine, the combination of impression mechanism, a web-support movable relative to said impression mechanism, means adapted to feed a web at 115 a normal rate relative to said support, means adapted to grip a portion of said web and cause said support to move, thereby varying the speed of said web relative to said impression mechanism, and means adapted to sever said web into sheets.

34. In a web-printing machine, the combination of impression mechanism, a web-support movable relative to said impression mechanism, means adapted to feed a web at 125

a normal rate relative to said support, means adapted to grip a portion of said web and cause said support to move, thereby varying the speed of said web relative to said impression mechanism, means adapted to sever said web into sheets, and means adapted to adjust said severing means so as to sever the web into sheets of different lengths.

Signed at Stapleton, in the county of Richmond and State of New York this 25th 10 day of Nov. A. D. 1908.

FREDERICK M. TURCK.
